E. M. Talbot

Attorney

UNITED STATES PATENT OFFICE.

CHARLES L. WEST, OF FRANKLIN, NORTH CAROLINA.

PILE LIFTER.

Application filed September 13, 1922. Serial No. 588,051.

To all whom it may concern:

Be it known that CHARLES L. WEST, a citizen of the United States of America, residing at Franklin, in the county of Macon and 5 State of North Carolina, has invented new and useful Improvements in Pile Lifters, of which the following is a specification.

The object of the invention is to provide a grapple or engaging means suitable for use 10 in connection with cement or concrete piles particularly of the reinforced type for facilitating the lifting, moving and positioning thereof through the agency of hoisting mechanism or tackle; and particularly to 15 provide a simple and efficient device which may be attached to a reinforced concrete pile and interchangeably and successively applied to a number of such piles as a convenient means for engagement by hoisting 20 mechanism in handling the piles; and with these objects in view the invention consists in a construction and combination of parts of which a preferred embodiment is shown in the accompanying drawings, wherein:—

25 Figure 1 is a side view partly in section of a reinforced concrete pile and a lifter constructed in accordance with the invention applied in the operative position thereto, and also indicating the grappling feature of 30 a hoisting mechanism in engagement with the lifter.

Figure 2 is a plan view of the same.

Figure 3 shows a modified construction of attachment for the hoisting mechanism.

35 The lifter consists essentially of a bar 10 adapted for arrangement upon the end of a pile 11 which is to be elevated, carried or positioned, and which is provided with reinforcing bars or rods 12 preferably extended beyond the upper end of the body portion 40 of the pile to afford the projecting terminals 13. Said lifter bar is provided with openings 14 to receive said projecting terminals of the reinforcing bars and disengagement 45 of said bar from these terminals is prevented by suitable holding means such as collars 15 fitted on the terminals and provided with set-screws 16 to lock them in place.

At its center the lifting bar is arched as 50 shown at 17 to afford clearance beneath the

same to permit of engagement with the arch of a hoisting hook or ring 18 with which may be engaged the hook 19 at the end of a hoisting cable 20 actuated by any suitable hoisting mechanism, not shown.

55 In the modified construction illustrated in Figure 3 the hoisting hook or ring 18^a is attached to a bolt 21 extending through the arch 17^a of the lifting bar 10^a.

Having positioned the lifting bar on the 60 upper end of the pile it is obvious that engagement of the hoisting cable therewith may be readily effected, and after the pile has been positioned the lifting bar may be detached and applied to another pile for 65 similar manipulation, to the end that the setting of a series of piles in connection with a proposed structure or breakwater may be effected with facility.

A further and important utility of the 70 reinforcing bars or rods 12 which are extended terminally beyond the end of the body portion of the pile to afford an anchorage for the lifting bar is that they serve equally as an anchorage for the cushion which is ordinarily placed on the end of the pile to receive the direct impact of the pile driver to 75 protect the end of the pile. Any of the the ordinary types of cushions may be employed in this connection provided they are punctured or provided with openings to receive the projecting ends of the reinforcing rods to the end that the cushion is thereby held against lateral displacement during the driving of the tool.

80 Having described the invention, what is claimed as new and useful is:—

1. A reinforced concrete pile lifter having a lifting bar for arrangement in contact with the upper end of the pile and provided with means for engaging the same, and a hoisting ring or hook connected with said bar at an intermediate point for engagement by the hook of a hoisting cable, the lifting bar being provided with openings 90 for the reception of the extended terminals of the pile reinforcing rods, and means provided for holding said bar in engagement with the rods.

95 2. A reinforced concrete pile lifter having 100

a lifting bar for arrangement in contact with the upper end of the pile and provided with means for engaging the same, and a hoisting ring or hook connected with said bar at an intermediate point for engagement by the hook of a hoisting cable, the lifting bar being provided with openings for the re-

ception of the extended terminals of the pile reinforcing rods, and collars engaging said rods for securing the lifting bar in ¹⁰ place thereon.

In testimony whereof he affixes his signature.

CHARLES L. WEST.
